UNITED STATES PATENT OFFICE.

FREDERICK GALE, OF LANCEFIELD, VICTORIA, AUSTRALIA, ASSIGNOR OF ONE-HALF TO JOHNSTON HEMPHILL, OF LANCEFIELD, VICTORIA, AUSTRALIA.

ATTACHMENT FOR PLOWS.

SPECIFICATION forming part of Letters Patent No. 734,846, dated July 28, 1903.

Application filed November 12, 1901. Serial No. 81,966. (No model.)

To all whom it may concern:

Be it known that I, FREDERICK GALE, a subject of King Edward VII of Great Britain and Ireland, residing at High street, Lancefield, in the State of Victoria, Australia, have invented certain new and useful Improvements in Attachments for Plows, of which the following is a specification.

This invention comprises improvements upon an earlier invention by me, (application Serial No. 39,616, filed December 13, 1900, in the United States, for machines for sowing, manuring, and harrowing, in combination with plowing.) Where this invention is applied to a single furrow-plow the hopper mechanism will be driven by any means well known in this class of invention; but in a plow of two furrows or more the arrangement preferred is illustrated in the drawings herewith, exhibiting important differences from the earlier invention above named.

Figures 1 to 3 are on half, and Figs. 4 to 7 on double, the scale of Figs. 8 and 9. In various figures some parts are broken away or omitted to clearly show other parts.

The same characters of reference in all the figures indicate like parts.

In the drawings, Fig. 1 is a side view of part of plow with this invention applied; Fig. 2, 30 plan of parts in Fig. 1, and Fig. 3 back end elevation of same; Fig. 4, a detail of harrow-fastening; Figs. 5 and 6, seed-feed wheel in side view and vertical transverse section, respectively; Fig. 7, vertical section through manure-feed wheel, its apertured cover, and part of hopper-base; Fig. 8, plan of combined seed and manure hopper; Fig. 9, side view of seed-compartment in vertical section.

In the drawings the same characters of reference are used to indicate like parts.

a is a two-compartment hopper attached above the main frame, as to a beam *z*, of the plow by any suitable standard *b*, duly clamped or secured to said beam, as by clamp *c*, and bolted to the hopper. To the furrow-wheel *d* of the plow is attached (either to its arms or around its spindle) a toothed wheel *e*. Another toothed wheel *f*, the support of which is a hanger *g*, is geared to said wheel *e*. The top 45 of hanger *g* is secured, as by a clamp *h*, to the frame *z*. A light sprocket-wheel *i* and any

suitable clutch, as at *j*, for putting it in or out of operation, the construction of which will be well understood by competent mechanics, are provided on the spindle of the 55 wheel *e*. Details such as the handle of the clutch are not shown, no claim thereto being made. By moving the clutch the attendant stops when required the said sprocket-wheel *i*, and thereby stops the seed-feed wheel and 60 manure-feed wheel, which take their motion from the said or primary sprocket-wheel *i*, as next explained.

k is a chain connecting wheel *i* with a sprocket-wheel *l* on a spindle *p*, which passes 65 across beneath the rear hopper *a* and which has on it another sprocket-wheel, *m*, a chain *n*, from which engages a sprocket-wheel *o* on another spindle, *q*, similar to *p*, but under another hopper, *a*, so that the spindles of both 70 hoppers will turn simultaneously and equally fast, and so on for as many hoppers as are in use on the implement.

In practice I would use several sprocket-wheels *l*, differing in diameter (see Fig. 2) and 75 adjustably slidable on spindle *p*, so that any desired sized sprocket can be brought in place to receive chain *k* and can be temporarily fixed or keyed on the spindle in that position. Any suitable tension-pulley (not shown) is 80 provided to keep chain *k* taut. Each hopper-spindle, as *p* *q*, aforesaid is provided with a worm *r*, which is geared to a pinion *s*, which works in a suitable bearing at the base of the hopper and is connected to a manure-feed 85 wheel *t*, as at the center aperture *u*, which receives the top of the pinion-spindle. Wheel *t* turns in an annular well *v* at the base of the manure-compartment of the hopper, to which base the sides all around slope. An aperture 90 *w* is provided in the well-center to enable the pinion to be dropped through the same into place. The wheel *t* has all around its edge sheet-metal vanes, cutters, or teeth *y*, each forming the outside of a somewhat triangular 95 pocket. After pinion *s* is put in place and wheel *t* put over and secured to it, as by a nut, for the purpose next described, then a centrally-open plate *l*, which is of slightly larger diameter than well *v*, is put over the 100 wheel *t* and is rested so that it cannot turn or rise on the same and on the sides of said

well. If any hard foreign substance which the vanes cannot divide gets in their path, then the wheel t will stop, the connection, as said nut, to the pinion being so arranged that it may loosen and enable the pinion to continue moving. The attendant may then in due course remove the obstruction and tighten the nut. 2 is a side enlargement (of the central aperture in plate 1) above the teeth 10 or vanes y . The manure which is in the hopper above said plate cannot get to or meet the vanes y except through this aperture 2, which is made comparatively small. This prevents excessive discharge of manure and clogging 15 of the vanes. 3 is a small aperture in the base of well v , but not central, and this is provided with a comb edge 4. This aperture 3 is the only exit for the manure, and it is so located as not to be directly under aperture 2. 20 The manure has thus to be carried around some distance by vanes y before it can reach aperture 3. If it is desired to reduce the amount of manure fed, a wheel t may be inserted having smaller pockets. The manure used, though normally floury, will, if lumpy, be 25 disintegrated by the vanes or cutters and the comb 4 before it leaves the manure-compartment 5. In cases where the comb 4 does not insure the manure dropping in a sufficiently- 30 divided state a finer comb may be substituted or finer divisions of the space 3 be otherwise produced. A door 6 (hinged at its base) forms a division between the compartment 5 and the seed-compartment 7, and this door 35 when shifted from its normal vertical position and allowed to fall down on one side, as seen in Fig. 8, has the effect of enlarging compartment 5 and closing compartment 7, and this is done when desired when manuring is not required. The rate of the manure-feed is regulated by the diameter of whichever sprocket-wheel l is in gear with chain k at the time. The seed-compartment 40 has each of its sides sloping to its base, at 45 which is a small aperture for the discharge or exit of seed. This aperture is in two parts, (marked 11 and 12,) the latter being the shorter, between which parts is a door 13, which in practice is to be hinged so that it 50 can be dropped to either side, thus completely closing either part of the aperture. Part of the edge of a seed-feed wheel 14, which is fixed to the hopper-spindle, as p , fits up into this aperture, (it is important it should project up into the part 11,) preventing seed dropping out vertically and also enabling the wheel 14 as it revolves to carry out of the hopper, by reason either of the pockets 15 or the groove 16, (both sides of which groove are 55 fluted,) a regular quantity of seed.

40 is the land-wheel, 39 the operating-lever therefor, and 41 represents the stays for the mold-board. The clutch j is formed by a number of projections or pins on the spindle of f 60 and a single projection (inclosed by a revolute ferrule to reduce friction) at right angles thereto on the spindle of the sprocket-wheel i .

An arm 42 is provided, one end of which is adapted to press against the side of wheel i , and by causing this arm to move the attendant may connect wheel i with the clutch j . 70 43 is a short crank jointed to 42 and fastened on the hereinafter-described bent lever 36. When 36 is moved, one end of arm 42, near wheel i , pushes the latter over until the projection on it engages between two of the projections of the clutch on f . This pushing motion (or the reverse) is brought about by an arm 44, one end of which is pivoted to some fixed support and the other end fastened to 80 arm 42, as seen in Fig. 2. The attendant lowers lever 39, Fig. 1, to lower harrows 28 and put wheel l (per clutch j) in motion. The manure from compartment 5 enters a wide-topped funnel 10, the base of which is 85 loose in the head of a flexible tube 8, leading thence loosely to the funnel of metal fixed on top of drill or furrow-opener 9. A peculiarity of wheel 14 is that it has at least three provisions for feeding seed, the addition being a toothed recessed side or sides 17, Figs. 5, 6, and 9. Where neither pockets 15 nor groove 16 will do, as when the seed is ill dressed, the side feed 17 is used. A special seed-chamber 18 is provided, (reached by aperture at 19 in hopper a ,) which can be closed by a large door 20, the open and closed positions of which are shown by firm and dotted lines in Figs. 8 and 9. As by chamber 18 seed is admitted to one side 17 of the seed-feed wheel, the wheel can 95 be reversed, so as to use either side at will. The exit from chamber 18 at its base is a narrow channel 21, wheel 14 carrying seed against the wall 22 of the chamber and forcing the seed out of channel 21. Thus chamber 18 is 100 a force-feed chamber from which seed drops into the wide-topped funnel 10, just as from apertures 11 and 12. Seed and manure pass by funnel 10 together to drill 9, having oblique rear exit 23. Each drill has a bar 25, the rear 105 of which is fixed to the drill and the front of which is pivoted to an attachment 26 to the moldboard, as by a pin passing through a hole located at a suitable height. Instead of these attachments being supported by the moldboard, they may, however, be supported by a plow-beam or some suitable piece of framing. A guide 27, having a bifurcated or slotted top, is also attached to the moldboard 24, the slot 110 keeping bar 25 longitudinal, while allowing the drill to rise and fall on its pivot. Of the harrow-blades 28 one or more are made with an opening 29, Fig. 1, the inside back edge of which is valuable as a second cutter of clods or lumps of earth. The connection of the 115 harrow-blades to the upper plate 30 is adjustably effected. Each plate 30 has bolt-holes through which bolts 32 pass and are held by nuts or the like. The harrows are fixed in any position required, (see Fig. 4 on four times 120 the scale of Fig. 2,) there being transverse arms 31 integral with the harrows holding down the head of bolt 32, which when central is in a recess 33 in harrow. Plate 30 may 125

be of any shape and length to carry any desired number of teeth in such position as may be suitable. The harrow-plates 30, connected by a rod 34, are now raised when required by improved means. Rod 34 is engaged by a spring-fork—that is, one leg of it exerts spring-pressure toward the other leg—on an arm 35, forming one end of bent lever 36, which has each end bent downwardly, the middle being suitably supported as to cross-bar 37. The other end of the bent lever terminates in a wide lug 38, set in the path of the lower end of main lever 39. When turning a head-land or ceasing for the time to plow, the various cultivating parts are easily lifted from the ground.

As to the form, relative sizes, number, and positions of the parts modifications may be made which adhere to the spirit of the invention.

What I claim as my invention, and desire to secure by Letters Patent of the United States, is—

1. In an attachment for plows, the combination of an open-bottom hopper, and a seed-feed wheel carried beneath said hopper, said feed-wheel being provided with a V-shaped fluted groove, and with pockets on its periphery, and also provided with side pockets for feeding seed, substantially as described.

2. In an attachment for plows, the combination of a plow-frame, a hopper mounted thereon, provided with two discharge-apertures, seed and manure feed wheels mounted beneath said apertures respectively, said feed-wheel having a V-shaped fluted groove and pockets on its periphery and also provided with side pockets, a swinging door between said feed-wheels, and a plurality of swinging doors located at right angles to each other and arranged above said seed-feed wheel, substantially as described.

3. In an attachment for plows, the combination of a plow-frame, a hopper mounted thereon, provided with two discharge-apertures,

manure and seed feed wheels carried beneath said apertures, said seed - feed wheel being provided with a groove, and with pockets on its periphery, and having a toothed recessed side, and a plurality of swinging doors arranged above said seed-feed wheel at right angles to each other, substantially as described.

4. In an attachment for plows, the combination of a plow-frame, a hopper mounted thereon, provided with an aperture for the discharge of seed, and a seed-feed wheel mounted beneath said aperture, and provided with three separate means for feeding the seed, a V-shaped fluted groove, a row of pockets on its periphery, and a toothed recessed side, substantially as described.

5. In an attachment for plows, the combination of a plow-frame, a hopper mounted thereon, provided with a seed-discharge aperture, a seed-feed wheel carried beneath said aperture, said wheel being provided with a V-shaped fluted groove and with a row of apertures on its periphery, and also provided with a toothed recessed side, and swinging doors arranged in said hopper above said feed-wheel at right angles to each other, substantially as described.

6. A seed-feed wheel having seed-pockets and a peripheral groove and recesses in its lateral faces and provided with teeth.

7. The combination with a drill, a bar 25, one end of which is fixed to the drill, an attachment 26 for the moldboard, to which attachment the other end of the bar is pivoted, and a guide 27 having a bifurcated top attached to the moldboard, all as and for the purpose specified.

In testimony whereof I have hereunto set my hand in presence of two subscribing witnesses.

FREDERICK GALE.
